UNITED STATES PATENT OFFICE

2,307,245

COMPUTING AND PRINTING MACHINE

Oscar J. Sundstrand, West Hartford, Conn., assignor to Underwood Elliott Fisher Company, New York, N. Y., a corporation of Delaware

Original applications December 18, 1931, Serial No. 581,800, and April 28, 1937, Serial No. 139,538. Divided and this application June 27, 1940, Serial No. 342,738

4 Claims. (Cl. 235—145)

The present invention relates to computing and printing machines and is illustrated on the type of machine employing a traveling paper carriage and a group of vertically movable type bars. This case is a division of my copending application Serial No. 139,538, filed April 28, 1937, which application is a division of application Serial No. 581,800, filed December 18, 1931, which issued into U. S. Patent No. 2,194,270 on March 19, 1940. This divisional application relates to keyboard mechanism, and more particularly to the means for controlling the movement of the actuators, the means for restoring this controlling mechanism, and the means for selectively releasing various keys.

With these and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a plan view of a bookkeeping machine embodying the features of my invention.

Figure 2 is a fragmental elevation of the type bar mechanism.

Figure 3 illustrates the signal type bar and the characters printed thereby.

Figure 4 is a fragmental phantom view of the four type bars farthest to the left.

Figure 5 is a fragmental plan view showing the connections between the type bars and the keyboard.

Figure 6 is a fragmental perspective view showing two of the stops comprised in one of the character sections,

Figure 7 is a fragmental perspective view of the three left-hand character sections, looking from the rear of the machine.

Figure 8 is a fragmental perspective view of the stop mechanism comprised in the middle character section,

Figure 9 is a left-hand side elevation of the "Months" character key bank, and shows parts of the key restoring mechanism.

Figure 10 is a fragmental perspective view of the character sections and the means for releasing operated character keys,

Figure 11 is a fragmental perspective view illustrating a means for adjusting the character key releasing mechanism.

Figure 12 is a right-hand elevation of the middle character section, i. e., the section that controls the printing of the numbers of the days of the month,

Figure 13 illustrates the latch mechanism and stop mechanism for the units keys used in setting up the numbers of the days of the month,

Figure 14 shows the latching mechanism and stop mechanism for the tens keys used in setting up the numbers of the days of the month,

Figure 15 is a plan section on line 15—15 of Figure 13.

Figure 16 illustrates the latching mechanism and stop mechanism associated with the keys used in setting up various bookkeeping symbols,

Figure 17 is a plan section on line 17—17 of Figure 16, and

Figure 18 represents the latching mechanism and the stop mechanism for the two keys used in setting up the numbers denoting two years.

General description

The machine illustrated in the accompanying drawings is of the key set, motor operated type, having one adding and subtracting totalizer (cross-footer) and four totalizers capable of adding (registers). Folio numbers and amounts are entered by the use of "10 key" keyboards, and the dates and characters are printed by the use of keys situated in parallel banks generally similar to the "81 key" keyboard construction.

Actuators or type bars

The type for printing items, totals, dates, folios, etc., upon the work pieces are carried by type bars or actuators, of which there may be any desired number. Herein there is a type bar 1 (Figure 1) for printing symbols or "signals" to denote the character of the amount or to indicate that a particular counter is clear, nine type bars 2 for use in printing amounts and for printing two naughts to signify that a counter is clear, four type bars 3 for printing folios, and four type bars 4 for printing dates and various abbreviations used in bookkeeping.

In this instance, the type bars or actuators 1, 2, 3 and 4 have a rectilinear vertical movement. They are guided by a rod 5 (Figure 2) fixed in the machine frame and extending through a slot 5a in each of the type bars, a bar 6 secured in the machine frame, and a plate 7 likewise fixed in the machine frame, said plate having vertical slots through which brackets 8 fixed to the type bars extend. Each type bar has a rearward extension 9 having at its rear end a lug 10 that extends through a vertical guide slot in a plate 11 fixed in the machine frame.

The means for raising the type bars includes a plurality of levers 12, one for each type bar, said levers being pivoted in the machine frame as illustrated in U. S. Patent No. 2,194,270. The forward arm of each lever 12 has a pin and slot connection with the bracket 8 on the corresponding type bar. A coiled spring tends to move the lever in the direction to raise the type bar.

Forwardly extending arms such as 516 and 532 are pivoted to the lower ends of the type bars

and carry upstanding pins such as 515 and 501. The pins are suitably guided for vertical movement, and are arranged to be stopped in their upward movement by settable stops as will hereinafter be described.

Character keys

At the left of the keyboard are three banks of character keys. These keys are latched in depressed position during a given cycle of operations of the machine by slides such as 505 (Figure 13) reciprocable longitudinally of the machine and having lugs 211 thereon. Each lug has a beveled surface 212 and a locking shoulder 213. On each of the key stems is a locking lug 214 having a beveled surface to engage the surface 212 when the key is depressed, and thus push the slide forward to allow the lug 214 to engage beneath the shoulder 213 when its respective slide is drawn rearwardly by a spring such as 505a. Near the end of the cycle of operations the slide 505 is drawn forward to release the key to the action of the key restoring means.

The key restoring means consists of a bell crank such as 216 (Figure 12) pivoted at 217, one arm of the bell crank engaging the stem of its associated key, and the other arm being pivoted to the forward end of a slide such as 517. The rear end of the slide is guided in the frame work. An expansive spring 219 (Figure 8) holds the slide 517 in its forward position, thus holding the key elevated. Depression of a key compresses spring 219 and moves slide 517 to the rear. These parts are held in this position until the key restoring mechanism is operated. When the slides such as 505 (Figure 13) are drawn forward to release the depressed keys, springs 219 (Figure 8) return slides 517 (Figure 12), the bell cranks 216, and their corresponding keys, to their normal undepressed position.

The bank of twelve keys 498 (Figure 1) at the extreme left are used in printing the names of the months. The keys in this bank are arranged to be locked by a slide 499 (Figure 9). Each key 498 operates a slide similar to the slides 517 (Figure 12), one tine of the fork at the rear end of each of said slides serving as a stop 500 (Figure 7) to limit the upward movement of a pin 501 connected to an arm 502 (Figure 9) pivoted to the lower portion of the type bar 4 that is farthest to the left (see Figure 5). This type bar has twelve type adapted to print abbreviations of the names of the months (see Figure 4). The rear end 499a (Figure 9) of the slide 499, when in its normal or ineffective position, serves as a stop to keep the pin 501 from rising. When any one of the keys 498 is depressed, the slide 499 is moved and held far enough forward for its rear end to be out of the path of upward movement of the pin 501.

The keys in the middle bank at the left hand side of the keyboard are used in printing numerals indicating the days of the month. The printing of the units digits "1" to "9," inclusive, is controlled by nine keys 503 (Figure 12) having key stems 504 arranged to be latched in depressed position by a slide 505. A spring 505a normally holds said slide in its rear position. On the rear end of said slide is a stop portion 506 (Figures 13 and 15) located in the path of the upward movement of a pin 507 connected to an arm 508 hinged to the lower portion of the type bar 4 that lies third from the left (Figure 5). This type bar carries ten numeral type, as indicated in Figure 4. The stop 506 is located so as to limit the rising

movement of the type bar to the point where the cipher type is positioned at the printing line.

Connected to each of the keys 503 is a slide 517 having at its rear end a fork, one tine of which constitutes a stop 510 (Figure 7) to limit the upward movement of the pin 507.

The printing of the tens digit in the number of the day of the month is controlled by three keys 511 (Figure 12) having key stems 512. The keys 511 are arranged to be latched in depressed position by a slide 513 (Figure 14), said slide being urged rearwardly by a spring 513a. The rear end of said slide constitutes a stop 514 for a pin 515 connected to an arm 516 (Figure 5) pivoted to the type bar 4 that lies second from the left end. When the slide 513 is in its normal position, the stop 514 prevents upward movement of said type bar, but when said latch is operating to hold one of the keys 511 depressed, the stop portion 514 is out of the path of upward movement of the pin 515. Said type bar carries three numeral type, as shown in Figure 4.

Each of the keys 511 is connected to a slide 517 (Figure 12) having at its rear end a fork, one tine of which forms a stop 518 (Figure 8) for the pin 515.

The third bank from the left controls the printing of the numbers denoting, say, two years, also a variety of symbols used in bookkeeping work. Herein I have shown the two upper keys in this bank as arranged for controlling the printing of "30" and "31." These year keys are indicated at 519 (Figure 1) and have key stems 520 (Figure 18) arranged to be latched in depressed position by a slide 521. Said slide is urged rearwardly by a spring 521a. The keys 519 are connected to slides 522 (Figure 6) having at their rear ends forks, one tine of each of which serves as a stop 522a to limit the rising movement of a pin 523 connected to an arm 524 (Figure 5) hinged to the lower portion of the type bar 4 farthest to the right as viewed in Figure 5.

The remaining keys in this bank are denoted by the number 523 (Figure 1). They have key stems 526 (Figure 16) arranged to be latched down by a slide 527. A spring 527a tends to move the slide 527 rearwardly. The rear end of said slide forms a stop 528 which, when the slide is in its normal position, serves to prevent the pin 523 from rising. When the slide 527 is acting to hold one of the keys 525 down, the stop portion 528 is out of the path of upward movement of the pin 523.

To each of the key stems 526 is connected a slide (similar to 517 in Figure 12) having at its rear end a fork. One tine of each fork constitutes a stop 529 (Figure 7) to limit upward movement of the pin 523.

The beveled lugs 530 (Figure 18) arranged to be engaged by the slide 521 for the purpose of locking either of the two year keys down, are also arranged to operate against beveled surfaces 531 (Figure 16) on the slide 527, for the purpose of moving the slide 527 forward far enough to withdraw the stop 528 from the path of the pin 523. Depression of any one of the symbol keys 525 serves to move the slide 527 forward a further slight extent to permit of latching said symbol keys down.

A row of operation controlling keys 430, etc. (Figure 1) is situated at the right hand side of the keyboard for controlling the various machine functions, such as non-adding, totaling, subtotaling, etc. The various functions of these keys are covered in the before mentioned U. S. Patent

No. 2,194,270, and will, therefore, not be discussed here. The manner in which the depression of these keys controls the printing mechanism and also the manner in which they are latched down and restored is similar to the manner in which the three rows of keys at the left of the keyboard control the printing mechanism, so this also need not be discussed.

Releasing character keys

The bank of operation controlling keys at the right side of the keyboard and the three banks of character keys at the left side of the keyboard are released to the restoring action of their respective restoring springs in the following manner.

A plate 220 (Figure 10) is pivoted along its upper edge to the machine frame. The pivotal support consists of brackets 220a secured to plate 220 and having rearwardly extending projections 220b (Figure 13) overhanging a stationary plate 220c on the machine frame. The lower edge of the plate 220 (Figure 10) at the right hand side of the machine engages behind a lug 221 on a slide 210 for the bank of operation controlling keys, and behind lugs 532 on the slides 499, 505, 513, 521 and 527 for the keys at the left side of the keyboard. Near the end of the cycle of operations, the plate 220 is thrown forward by a slide 222 guided in the machine frame for movement longitudinally of the machine. Spring 223 normally holds the slide 222 in its rearward position. A pin 224 is secured to an arm 88 secured in turn to the oscillating drive shaft 17 that receives a clockwise and then a counter-clockwise oscillation during each operation of the machine. Pin 224 engages the rear end of slide 222 and pushes it forward, on its return oscillation, thereby tilting plate 220 forward by the forward end of slide 222 abutting the left end of plate 220. When slide 222 is thus moved forward, a cam surface 225 thereon rides over a stationary cam surface 226 and thereby raises the rear end of slide 222 sufficiently to allow it to be free of the pin 224, whereupon spring 223 returns slide 222 to its normal rear position.

This forward movement of the lower edge of plate 220 pulls the slides 499, 505, 513, etc., forward, and moves the locking shoulders 213 (Figure 13) from above the lugs 214 on the stems of the depressed keys, allowing the key restoring springs 219 (Figure 8) to restore the keys as mentioned above.

In the present embodiment of the invention, the operation-controlled keys at the right hand side of the keyboard and the ten symbol keys 525 are automatically released at the conclusion of every cycle of operations of the machine. Means is provided whereby the remaining keys in the three banks of character keys may be released or held depressed as desired. It will be noted in Figure 10 that the lower edge of the plate 220 has notches 533, 534 and 535 therein. A manually operable lever 536 (Figure 11) is pivoted in the framework at 537. Fixed to said lever is a pin 538, one end of which lies within a notch 539 in the plate 220. It will be seen that when the lever 536 is swung toward the right, the plate 220 will be also slid toward the right so as to bring the notch 533 into register with the slide 499, the notch 534 into register with the slides 505 and 513, and the notch 535 into register with the slide 521, it being noted that the pivotal sup-

port of plate 220 permits of such sliding movement. A spring actuated detent 539a (Figure 11) yieldingly holds the clearing plate 220 in either of its two positions. With the plate 220 thus positioned, pivotal movement of said plate will not cause forward movement of the slides 499, 505, 513 and 521, and consequently the keys which may have been latched down by those slides will not be released.

10. Manually operable means is provided for releasing the keys in the four banks of keys. This means comprises a clear key 540 (Figures 1 and 10), the stem of which has a lug 541 arranged to bear against an arm 542 fixed to the upper edge of the plate 220. A tension spring 543 normally holds the key 540 elevated. It will be seen that depression of the clear key 540 will release the keys in accordance with the position that may be occupied at the time by the plate 220.
20. While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. A printing machine comprising, in combination, a plurality of parallel banks of keys, a slide for each of said banks, said slide serving to hold any key in its bank depressed, a member engaging all of said slides to move the latter out of effective position, said member having a notch therein, and manual means for shifting said member to bring said notch into register with one of said slides to deprive said member of control of the slide.

2. A printing machine comprising, in combination, a plurality of parallel banks of keys, a slide for each of said banks, said slide serving to hold any key in its bank depressed, a member engaging all of said slides to move the latter out of effective position, said member having a notch therein, manual means for shifting said member to bring said notch into register with one of said slides to deprive said member of control of the slide, and means operable in the cycling of the machine for pivotally moving said member.

3. A printing machine comprising, in combination, a plurality of parallel banks of keys, a slide for each of said banks, said slide serving to hold any key in its bank depressed, a plate pivoted at one edge to swing on an axis transversely of said banks of keys, the other edge of said plate being arranged to engage all of said slides to move the latter out of effective position, said other edge having a notch therein, manual means for axially shifting said plate to bring said notch into register with one of said slides, whereby to deprive said plate of control of such slide, and means operable in the cycling of the machine for pivotally moving said plate.

4. The combination of a series of keys, means for latching any one of said keys in operated position, a pivoted member arranged to engage said means, means for pivotally moving the said member to move the latching means out of effective position, and manually operable means for moving said pivoted member axially out of position to engage said latching means.
